UNITED STATES PATENT OFFICE.

WALTER F. TROTTER, OF CHARLESTON, WEST VIRGINIA, ASSIGNOR, BY MESNE ASSIGNMENTS, TO THE JEFFREY MANUFACTURING COMPANY, A CORPORATION OF OHIO.

RECIPROCATING-TOOL MECHANISM.

1,168,834.

Specification of Letters Patent. Patented Jan. 18, 1916.

Application filed September 20, 1907, Serial No. 393,835. Renewed June 17, 1915. Serial No. 34,739.

To all whom it may concern:

Be it known that I, WALTER F. TROTTER, a citizen of the United States, residing at Charleston, in the county of Kanawha and State of West Virginia, have invented certain new and useful Improvements in Reciprocating-Tool Mechanism, of which the following is a specification, reference being had therein to the accompanying drawing.

This invention relates to improvements in tools of the class in which each has, as its principal operative part, a reciprocating body by which blows are imparted to the material which is being operated on.

As an example of the mechanisms which can be constructed with the improvements, a reciprocating drill is shown herein adapted for use in the cutting of rock, coal and similar materials.

Figure 1 is a longitudinal section of a rock-drill or coal-drill embodying the improvements. Fig. 2 is a top plan view partly in section. Fig. 3 is an enlarged side elevation of part of the operating mechanism. Fig. 4 is an enlarged perspective view of the eccentric shifting member. Fig. 5 is an enlarged sectional view of the worm wheel. Figs. 6, 7, 8 and 9 are enlarged sectional views, more or less diagrammatic in character, illustrating the different positions of the parts when in operation.

The tool selected for illustration in the drawings is of the class mounted upon wheels and provided with handles so that it can be readily manipulated by the operator.

The wheels are indicated by 1, 2.

3 indicates a rod serving as a carrier for the tool proper, such as a drill bit and stem. At the rear end the rod 3 is secured to the piston 5 which is fitted in the chamber 6 of a cylinder 7. The front end of the cylinder is closed by a head 9 which may be provided with a gland and stuffing box, if desired. In the present case the head, as shown, is provided with a sleeve extension 4 to guide the tool rod 3.

The upper part of the wall of the cylinder is shown at 11.

At 12 and 13 are respectively the front port and the rear port in the cylinder walls. Adjacent to the cylinder chamber 6 there is a valve chamber 32 having ports 15 and 16 in its walls, the former connecting by a duct 14 with the rear cylinder port 13, and the

latter by a short duct with the cylinder port 12.

17 and 18 indicate respectively the rear feed port and the front feed port of the valve chamber 32. In this chamber there are two valves 29 and 30, the former adapted to open and to close the ports 15 and 17 and the latter to open and to close the ports at 16 and 18. The valves 29 and 30 are secured to a valve operating rod 31 which extends through the metal at 31^a, and outside thereof is connected to the valve actuating gear to be described.

19 indicates a compression chamber within a cylinder 20. In this chamber is fitted the pump piston 22.

23 and 24 are ports in the walls of the pump cylinder or compression chamber, these communicating with each other through the duct 25.

26 and 27 are similar ports at the other end of the pump cylinder and communicating with each other through a duct 28.

The pump piston 22 is connected to the rod 36 which passes through the end wall 36' provided, if necessary, with a stuffing box or gland and connected to the cross-head 37 in the guide 35. To the cross-head is pivoted the pitman 38 which at the rear end is connected to the crank 39 on the main shaft 40, the latter being mounted in suitable bearings carried by the frame.

On the shaft 40 there is an eccentric 41 connected by a strap 41^a and a link 42 to the crank 45 on the shaft 44. The shaft 44 carries crank 46 which is connected to the valve rod 31. Means are provided for varying the throw and angular relation of the eccentric while the machine is in operation, in the manner and for the purpose herein-after set forth. The shaft 40 is rotated by the worm wheel 47 with which engages the worm 48 mounted on the armature shaft of the electric motor 49, the latter being shown conventionally in the drawing. The worm wheel 47 is rigidly secured to shaft 40 by means of the boss 47^a and the screws 47^b, as indicated in Fig. 5.

The eccentric disk 41 is movably mounted upon the face of the gear 47, being retained in position by the screw bolts 57-58 passed through the slots 59-60 in said gear. A large, elongated aperture or slot 41^c is formed in the eccentric disk and this slot receives an inner eccentric 61 which is ro-

tatably mounted upon the crank shaft 40. Eccentric 61 carries a hollow cylindrical extension 61' provided on its inner surface with a spiral cam groove 61^a. A sleeve 62 is mounted on the shaft 40, a spline 63 permitting free longitudinal movement of the sleeve but causing it to turn with the shaft. The hand lever 63^a pivoted on handle 53 constitutes means for moving the sleeve longitudinally on shaft 40, the forked ends 63' of said lever being slotted to receive pins carried by the ring 64, which is loosely mounted in a groove formed in the flanged end 62' of the sleeve.

15 62^a is a pin carried by sleeve 62 and engaging the spiral groove 61^a. When the sleeve 62 is moved longitudinally, the pin 62^a by engagement with the spiral groove causes the eccentric 61 to turn in respect to shaft 40 and so 20 to shift the eccentric proper 41, increasing or decreasing its throw according as the sleeve is moved outwardly or inwardly. The movement of the eccentric 41 with respect to the shaft 40 is determined by the slots 25 59—60 in which the screw bolts 57—58 are slidably mounted, and these slots are so shaped that the eccentric 41 is moved angularly with respect to the crank 39 at the same time that it is moved laterally across 30 the shaft. A spring locking finger 65 mounted on handle 53 and notched to engage the shifting lever 63^a serves to hold sleeve 62 in adjusted position.

35 The metal which provides the walls for the tool cylinder 7, the valve chamber 32 and the compression chamber 19, together with the guide at 35, can be in one piece constituting a frame for supporting the movable parts, and in the present instance the casting is also provided with arms 50 having depending brackets 50', the same carrying the shafts 40 and 44, respectively, and with trunnions 51, 52 upon which are mounted the wheels 1 and 2. The arms 50 also carry 40 the handles 53.

45 At 54 there is a valve in the head plate of the pump chamber mounted in a seat thimble 55 inserted into the plate. The valve is normally held in place by the spring at 56. 50 This valve acts to permit the entering of bodies of air from time to time to the interior chambers if the volume of air therein is decreased, through leakage or otherwise, to such an extent as to lower the pressure 55 below the desired limit.

60 A mechanism having parts constructed and related in the way described can be used as follows: By preference a volume of air is preliminarily stored in the interior chambers such as to furnish a pressure considerably above that of the atmosphere, and interior pressure of forty pounds being preferred. If now the motor be set in operation 65 the action of the parts will be as follows: Assuming that the movements com-

mence when the parts are in the positions shown in Fig. 6, the pump piston 22 starts forward, the valve pistons 29 and 30 at the same instant commencing to move rearward. The ports and ducts at 17, 18 are open and 70 also those at 15, 16 and 12, 13. There is at this time an equalization of pressure, in both parts of the circuit, that is, on both sides of the pump piston 22, this piston, at the instant referred to, leaving open both 75 the ports 23, 24 and their connecting duct 25. As soon as the piston 22 starts forward, however, the port 24 is closed and a relative increase of pressure is produced on the front 80 side of the piston. The air in front is forced across the valve chamber 32 into the forward end of the chamber 6, and the piston 5 and the tool move backward. When the pump piston 22 reaches the center of its stroke forward, the valve pistons 29 and 30 85 having completed their rearward stroke and again started forward are in the position shown in Fig. 7, while the piston 5 is still moving toward the rear, as indicated in said figure. Simultaneously with the increase of 90 pressure on the front sides of the pistons 22, 5 there is a decrease in pressure on their rear sides which assists in drawing the piston 5 backward. At the time the pump piston 22 reaches the forward end of its stroke, as 95 shown in Fig. 8, the tool-piston has reached the rear end of its chamber 6, and the valves 29, 30 close the ports 17, 15 and 18, 16. A small body of air is therefore cut off from 100 escape from the rear end of the tool cylinder 7 and the tool-piston is cushioned. While the piston 22 is in the forward end of the cylinder, as shown in Fig. 8, the pressure 105 on the pump chamber is equalized on both sides of the piston through the ports 26, 27 and the by-pass 28. By the time the pump piston has reached the central part, or points a little beyond the central part of its chamber, on its return stroke, the valves 29, 30 are reversed and open the portways 110 at 17, 15, 13 and 18, 16, 12, (see Fig. 9). At this instant a large volume of air in the rear 115 end of the pump chamber is under high compression and rushes rapidly to the rear end of the tool cylinder behind the tool-piston. This results in driving this piston and the tool forward with a powerful blow. The forward motion continues until the several parts have again reached the position indicated in Fig. 6. At this time there is a sufficient volume of air in the forward part of the tool cylinder to cushion the piston and tool on the forward stroke.

I prefer to so construct and proportion the 120 parts that, if the initial internal pressure throughout the circuit is forty pounds, the pressure behind the pump piston at the instant the valves 29 and 30 are opened shall be about 100 pounds. Just after the piston 22 reverses at the forward end of its stroke 125 131

and closes port 26 there will be considerable drop in pressure on its front side and in case of leakage or loss of air from the circuit said pressure may fall below that of the atmosphere. When this occurs the valve 54 yields inward under the higher external pressure and sufficient air is allowed to enter to restore the predetermined pressure. Obviously the mean normal pressure maintained in the closed circuit may be varied 10 by adjusting the tension of spring 56. When the pump piston is moving forward to effect the backward movement of the tool-piston 5, the ports across the valve chamber are 15 left open during the entire stroke of the pump piston and consequently the air on the forward side of the tool-piston will carry it backward without sudden or quick movements. That is to say, the cycle of 20 movement of the tool-piston comprises a relatively slow, uniform movement backward and a sudden, quick movement forward. The time at which the forward movement of the tool and its piston commences 25 can be varied by varying the movement of the valves through the eccentric-adjusting devices above referred to. By reason of the combined angular and lateral movement given to the eccentric by the shifting mechanism, the point in the cycle of operations 30 at which valves 29—30 close remains unchanged, while the point at which they open varies through a considerable range.

I prefer, under ordinary circumstances, to 35 have the valve 29 open the ports at 17 and 15 at about the half-way point of the travel of the piston 22, and under such adjustment the tool-piston makes a whole stroke while the pump piston is making a half 40 stroke. But it will be understood that the opening of the valves may be timed at will by the operator by means of the control-lever 63^a and the associated eccentric shifting mechanism, so that the strength of the 45 blow delivered by the tool may be varied in accordance with the changing character of the coal or rock being worked.

What I claim is:

1. In a reciprocating tool mechanism, the 50 combination with the tool cylinder and the piston therein, of a compressor comprising a cylinder and a piston, ducts leading from said compressor cylinder to the front and rear ends, respectively, of the tool cylinder, and means controlling the passage of air through said ducts timed to subject the front side of the tool piston to a relatively low effective pressure throughout one stroke of the compressor piston and the rear side 55 of the tool piston to a relatively high effective pressure during a part only of a succeeding stroke of the compressor piston.

2. In a reciprocating tool mechanism, the 60 combination with the tool cylinder and the piston therein, of a compressor comprising

a cylinder and a piston, ducts leading from said compressor cylinder to the front and rear ends, respectively, of the tool cylinder, and positively actuated means controlling the passage of air through said ducts 70 timed to subject the front side of the tool piston to a relatively low effective pressure during one stroke of the compressor piston and the rear side of the said tool piston to a relatively high effective pressure during 75 a part only of a succeeding stroke of the compressor piston.

3. In a reciprocating tool mechanism, the combination with the tool cylinder and the piston therein, of a compressor comprising 80 a cylinder and a piston, ducts leading from said compressor cylinder to the front and rear ends, respectively, of the tool cylinder, and positively actuated means controlling the passage of air through said ducts to subject the front side of the tool piston to a relatively low effective pressure during one 85 stroke of the compressor piston and the rear side of the tool piston to a relatively high effective pressure in a succeeding stroke of 90 the compressor piston.

4. In a reciprocating tool mechanism, the combination with the tool cylinder and the tool piston therein, of an air compressor comprising a cylinder and a piston, ducts leading from said compressor cylinder to the front and rear ends, respectively, of the tool cylinder, one of the ducts being open to conduct air from the compressor cylinder to one end of the tool cylinder during an 100 entire stroke of the compressor piston, means for closing said duct during the first part of the succeeding stroke of the compressor piston, and means for closing the other duct to prevent passage of air from the compressor cylinder to the other end of the tool cylinder during the first part of said succeeding stroke of the said compressor piston. 105

5. In a reciprocating tool mechanism, the combination with the tool cylinder and the piston therein, of a double acting compressor comprising a cylinder and piston, ducts leading from the respective chambers of said compressor cylinder to the front and rear ends, respectively, of the tool cylinder, means 110 controlling the passage of air through said ducts to subject the front side of the tool piston to a relatively low effective pressure during one stroke of the compressor piston and the rear side of the said tool piston to a relatively high effective pressure in a 115 succeeding stroke of the compressor piston, and means comprising a duct operative in at least one position of the compressor piston for placing the two chambers of the 120 compressor cylinder in communication with each other when said chambers are in communication with the front and rear ends, respectively, of the tool cylinder. 125

6. In a reciprocating tool mechanism, the 130

- combination with the tool cylinder and the piston therein, of a double acting compressor comprising a cylinder and a piston, ducts leading from the respective chambers of said compressor cylinder to the front and rear ends, respectively, of the tool cylinder, means controlling the passage of air through said ducts to subject the front side of the tool piston to a relatively low effective pressure 5 during one stroke of the compressor piston and the rear side of the said tool piston to a relatively high effective pressure in a succeeding stroke of the compressor piston, and means comprising a duct operative when 10 the compressor piston is in one of its extreme positions for placing the two chambers of the compressor cylinder in communication with each other when said chambers are in communication with the front 15 and rear ends, respectively, of the tool cylinder.
7. In a reciprocating tool mechanism, the combination with the tool cylinder and a piston therein, of a double acting compressor comprising a cylinder and a piston, ducts leading from the respective chambers of said compressor cylinder to the front and rear ends, respectively, of the tool cylinder, means controlling the passage of air through said 20 ducts to subject the front side of the tool piston to a relatively low effective pressure during one stroke of the compressor piston and the rear side of the said tool piston to a relatively high effective pressure in a succeeding stroke of the compressor piston, and means comprising a duct operative when 25 the compressor piston is in each of its extreme positions for placing the two chambers of the compressor in communication with each other when said chambers are in communication with the front and rear ends, respectively, of the tool cylinder.
8. In a reciprocating tool mechanism, the combination with the tool cylinder and the piston therein, of a double acting compressor comprising a cylinder and a piston, ducts leading from the respective chambers of said compressor cylinder to the front and rear ends, respectively, of the tool cylinder, means controlling the passage of air through said 30 ducts to subject the front side of the tool piston to a relatively low effective pressure during one stroke of the compressor piston and the rear side of the said tool piston to a relatively high effective pressure in a succeeding stroke of the compressor piston, and means comprising a duct operative when the compressor piston is at the end of its forward stroke.
9. In a reciprocating tool mechanism, the combination with the tool cylinder, and the tool piston therein, of an air compressor comprising a cylinder and a piston, ducts leading from the compressor cylinder to the front and rear ends, respectively, of the tool cylinder, means for opening and closing the said ducts, and a duct supplemental to the aforesaid ducts for conducting air from the front end of the compressor cylinder to the rear end thereof when the compressor piston is at the end of its forward stroke.

10. In a reciprocating tool mechanism, the combination with the tool cylinder, and the tool piston therein, of the air compressor comprising a cylinder and a piston, ducts between the front and rear ends of the air compressor cylinder and the front and rear ends, respectively, of the tool cylinder, duct-closing-and-opening means arranged to maintain the duct communicating with the forward end of the tool cylinder open during substantially the entire forward stroke of the compressing piston and closed during the first part of the rearward stroke thereof, and means to maintain the duct communicating with the rear end of the tool cylinder closed during the first part of the rearward stroke of the compressor piston.

11. In a reciprocating tool mechanism, the combination with the tool cylinder and the tool piston therein, of a double acting compressor comprising a cylinder and a piston, ducts leading from the respective chambers of said compressor cylinder to the front and rear ends, respectively, of the tool cylinder, means for opening and closing the said ducts at predetermined points in the movement of the compressor piston, means comprising a duct automatically operative in at least one position of the compressor piston for placing the two chambers of the compressor in communication with each other, and automatically acting means for admitting air from the external atmosphere to one of the compressor chambers.

12. In a reciprocating tool mechanism, the combination with the tool cylinder and the tool piston therein, of the air compressing cylinder, a piston therein, the ducts leading from the compressor to the front and rear ends, respectively, of the tool cylinder, the valves for opening and closing said ducts, the power shaft operatively connected to both the compressor piston and the valves, and means for varying the time of opening of said valves.

13. In a reciprocating tool mechanism, the combination with the tool cylinder and the tool piston therein, of the air compressing cylinder, a piston therein, the ducts leading from the compressor cylinder to the front and rear ends, respectively, of the tool cylinder, the valves for opening and closing said ducts, the power shaft operatively connected to both the compressor piston and the valves, and means for varying the time of opening of said valves without varying the time of their closing.

14. In a reciprocating tool mechanism, the combination of the tool cylinder and the tool piston therein, of the air compressing cylinder, a piston therein, ducts leading from the 5 compressor cylinder to the front and rear ends, respectively, of the tool cylinder, a valve mechanism for opening and closing the aforesaid ducts, a power shaft operatively connected to the compressor piston 10 and the said valve mechanism, and means for varying the time at which the valve mechanism opens the said ducts.
15. In a reciprocating tool mechanism, the combination with the tool cylinder and the 15 tool piston therein, of the air compressing cylinder, the piston therein, ducts leading from the compressor cylinder to the front and rear ends, respectively, of the tool cylinder, the valve mechanism for opening and 20 closing the aforesaid ducts, the power shaft operatively connected to both the compressor piston and the valve mechanism, and means for varying the time at which the valve mechanism opens said ducts without varying 25 the time at which it closes the same.
16. In a reciprocating tool mechanism, the combination with the tool cylinder and the tool piston therein, of an air compressor comprising a cylinder and a piston, ducts 30 leading from said compressor cylinder to the front and rear ends, respectively, of the tool cylinder, one of the ducts being open to conduct air from the compressor cylinder to one end of the tool cylinder during 35 an entire stroke of the compressor piston, means for opening and closing the last said duct and means controlling the passage of air through the other duct to cause the admission of air at a relatively high pressure 40 to the other end of the tool cylinder during the part only of a succeeding stroke of the compressor piston, and means comprising a 45 duct operative in at least one position of the compressor piston for placing the two chambers of the compressor cylinder in communication with each other when said chambers are in communication with the front and rear ends, respectively, of the tool cylinder.
- 50 17. In a reciprocating tool mechanism, the combination of the tool cylinder, the piston therein, the front air port 12 remote from the front end of the cylinder, the rear air port 13 closely adjacent to the rear head 55 of the tool cylinder, the duct leading to the port 12 having its inlet port 16 axially near the port 12, the duct 14 having its inlet port 15 relatively near the center of the stroke of the tool piston, the valves 29 and 30, for 60 the inlet ports 15 and 16 of the said ducts,
- the valve chamber for said valves extending to the front and to the rear of both of said inlet ports, means for actuating the valves, and means acting in coöperation with the valves to supply air under pressure to said 65 inlet ports alternately, substantially as set forth.
18. In a reciprocating tool mechanism, the combination of the tool cylinder, the piston therein, the front port 12, the rear port 13, 70 the valve mechanism controlling the said ports, the compressor piston, the compressor cylinder having ports communicating with the ports in the tool cylinder, and having at its ends respectively the by-pass ducts 25 75 and 28, with ports 23 and 27 respectively adjacent to the compressor cylinder heads, and ports 24, 26 respectively near the center axially of the compressor cylinder, and means for actuating the compressor piston 80 and the valve mechanism in timed relation so that the chambers of the tool cylinder are in communication with the chambers of the compressor cylinder when the latter are in communication with each other through 85 one or the other of the said by-pass ducts, substantially as set forth.
19. In a reciprocating tool mechanism, the combination of the tool cylinder, the piston therein, the ports at the front and at 90 the rear ends respectively of the tool cylinder, the valve mechanism controlling the said ports, the valve chamber, the compressor cylinder having the port 17 for delivering air to the rear end of the tool cylinder, 95 and the port 18 for delivering air to the front end of the tool cylinder, and having the by-pass ports 23, 24 and duct 25 at one end and the by-pass ports 26, 27 and the duct 28 at the other end, the valve 54 controlling communication with the external atmosphere, and means for actuating the compressor piston and the valve mechanism in timed relation so that the chambers of 100 the tool cylinder are in communication with the chambers of the compressor cylinder when the latter are in communication with each other through one or the other of the 105 said by-pass ducts, and so that the compressor cylinder chamber into which the valve 110 54 opens is closed at a time when said chamber is expanding with the movement of the compressor piston, substantially as set forth.

In testimony whereof I affix my signature, in presence of two witnesses.

WALTER F. TROTTER.
